UNITED STATES PATENT OFFICE.

JESSIE JACKSON ROBERTS, OF WINDER, GEORGIA, ASSIGNOR TO FLETCHER C. GRAD-DICK, OF WINDER, GEORGIA.

STOP ATTACHMENT FOR WARPING MACHINES.

Application filed February 18, 1922. Serial No. 537,654.

To all whom it may concern:

Be it known that I, JESSIE JACKSON ROBERTS, a citizen of the United States, residing at Winder, in the county of Barrow and the State of Georgia, have invented a new and useful Stop Attachment for Warping Machines, of which the following is a specification.

This invention relates to a stop attachment for warping machines and particularly to facilitate and insure falling or dropping of the drop wires having eyes through which the warp threads pass. These drop wires are loosely attached to the machine, so that when the yarn which passes through them is broken, they are supposed to fall and, through suitable interposed means, shift the gears of the machine and cause the latter to stop. In constructions now in common use these drop wires become clogged with dirt, dust, lint, trash and other foreign particles, so that they lose their free play or sensitiveness to dropping action and continue to stand in upright position when the yarn breaks, and as a consequence, the warping machine continues to operate and an extended break in the continuity of the yarn results.

The improved attachment embodying the features of the present invention causes a continual vibration of the drop wire bar and effects an elimination of a large part of the foreign matter that would otherwise adhere thereto, and when the yarn breaks, the drop wires will be free to immediately fall and instantaneously stop the machine. The improved attachment also serves as a bearing for operatively fixing the position of the drop wire bar and the rollers to which it is attached.

In the accompanying drawings:

Fig. 1 is a longitudinal section on the line 1—1, Fig. 2, of well known warping machine elements, showing the improved attachment applied thereto, a portion of the frame of the machine also being illustrated.

Fig. 2 is a top plan view of the structure shown by Fig. 1.

The usual form of drop wire bars A and A² are illustrated in the drawings and have a hollow formation with peripheral slots, as at a, through which project drop wires a' having outer looped terminals a² and movably associated at their inner ends with

relation to each bar by means of a central rod A', so that any one of the drop wires along the length of its bar A may be free to drop from an upright position as shown by Fig. 1 in full lines to the horizontal position illustrated by dotted lines and engage a shifting arm or lever B, which is connected as usual with suitable shifting gear or clutch mechanism as well understood in the art. Also included in the group of well known elements in warping machines is the roller C, which runs parallel with the bars A and A² and at a distance from the latter.

The improved attachment comprises a vibrating arm 1 having at one extremity an eye or hub 1^a, which is secured on the one bar A by means of a set screw 2. Depending from the hub or eye 1^a is a projection 3, and to the lower end thereof one terminal of a spring 4 is secured, the opposite terminal of said spring being attached to a portion 4^a of the frame. In the drawings a second bar A² is shown and has a hub or eye a³ secured thereto by a set screw 2^a, the hub or eye a³ having a depending arm 3^a similar to the arm 3 of the hub or eye 1^a heretofore described. Between the lower ends of the projections 3 and 3^a a link rod or connector 10 is interposed, so as to give the two bars A and A² a unitary action and also whereby both may be resiliently influenced by the spring 4. The bar A² is constructed similarly to the bar A and provided with drop wires a' having outer looped terminals or eyes a², this construction being in all respects similar to the wires of the bar A. The wires of the bar A² also cooperate with a shifting lever or arm B similar to that heretofore described and for the same purpose.

The vibrating arm 1 embodying the essential features of the invention extends over the hub or eye a³ on the bar A² and has an intermediate interiorly screw-threaded boss 11, in which is fitted a stop screw 8, held in its adjusted position by a jamb nut 9, the lower end of the stop screw 8 projecting below the lower edge of the arm 1 and adapted to forcefully engage the top portion of the hub or eye a³. The free end of the arm 1 is formed with a depending angular hook 12 having a lower curved edge 13 to engage a snail or analogous cam

5 secured on the roller C by a set screw 6 and having an angular drop 7. The roller C and the cam 5 rotate in the direction of the arrow shown in Fig. 1 and the 5 operation of this cam with relation to the arm 1 is against the resistance of the spring 4.

The warp threads are threaded or passed through the loops or eyes a^2 at the outer 10 free ends of the wires a' , the latter wires standing upwardly as shown by full lines in Fig. 1 and having warp threads passing therethrough as indicated by dotted lines. When the warping machine is in motion, 15 the roller C is regularly rotated in the direction of the arrow and the outer hooked end 12 of the arm 1 and the latter arm are gradually raised as the lower curved edge 20 of the hooked end 12 progresses over the inclined surface of the gradually rising part of the cam 5 until the said hooked end 12 reaches the drop 7, when the arm 1 is caused to suddenly fall through the action of the spring 4, and a positive vibration is not only 25 imposed on the bar A but likewise on the bar A^2 through the stop screw 8, which strikes or suddenly impacts against the upper eye a^2 . By this means the eyes or loops a^2 are almost entirely cleared of any 30 accumulations of lint, dirt, dust or other matter and will thus be maintained in condition for sensitive dropping action when either one of the warp threads engaging the eyes break, and as will be understood, when the warp threads engaging either one of the eyes becomes broken, the eye through which the broken thread passes will immediately fall and engage the upwardly projecting shifting arm B and stop the machine, 40 without any material damage or continued breakage of the same or other threads.

The improved attachment is shown in simplified form and is adapted to be applied to various types of warping machines by 45 simple changes in the mode of application, but in all of the applications of the improved attachment, the same essential features will be embodied and consist of the vibrating arm and the cam. The improved attachment also may be applied without modifying the structural features of the machine to 50 which it is applied.

What is claimed as new is:

1. The combination with a drop wire bar and a rotating part of a warping machine, 55 of a vibrating arm connected to the bar, to give a quick intermittent oscillatory motion to the latter, and a cam secured to the roller and engaged by the free end of the vibrating arm to instantly relieve the drop wires of accumulations and render them sensitive to automatic dropping action when the warp threads engaging the wires becomes broken.

2. The combination with a warping machine having a drop wire bar carrying a 60 plurality of drop wires with outer terminal eyes, a roller, and a stop projection, of a vibrating arm having one end applied to the drop wire bar and the opposite end formed with an angular projection, the arm 65 operating to give a quick intermittent oscillatory motion to the bar, a cam on the roller having an angular drop and engaged by the said angular projection of the vibrating arm, and spring means associated with the 70 vibrating arm for effecting a continuous vibration of said arm and elimination of lint and other accumulations from the eyes of the drop wires.

3. The combination with a warping machine having drop wire bars provided with loosely mounted drop wires having terminal eyes through which the warp threads are passed, a roller, and projections operatively 75 associated with the machine for stopping the latter, of a vibrating arm connected at one extremity to one of the drop wire bars and extending across the other drop wire bar and having a free angularly disposed 80 end, the vibrating arm having a depending projection and one of the drop wire bars having a similar projection, the two latter 85 projections being connected, the arm operating to give a quick intermittent oscillatory motion to the bars, an impacting stop device 90 engaging a portion of the projections on one of the drop wire bars, a spring connected to and controlling the vibrating arm relatively to both drop wire bars, and a cam with an angular shoulder secured on 95 the roller and continually engaged by the angular end of the vibrating arm.

JESSIE JACKSON ROBERTS.
